UNITED STATES PATENT OFFICE

143,334

DESIGN FOR A COMBINED RADIO CABINET AND CIGARETTE CONTAINER

Heidi Marienthal, New York, N. Y.

Application June 29, 1945, Serial No. 120,402

Term of patent 3½ years

(Cl. D56—4)

To all whom it may concern:

Be it known that I, Heidi Marienthal, a citizen of no country, but who has declared her intentions of becoming a citizen of the United States of America, residing in New York city, county of New York, and State of New York, have invented a new, original, and ornamental Design for a Combined Radio Cabinet and Cigarette Container, of which the following is a specification, reference being had to the accompanying drawing, forming part thereof, wherein,

Figure 1 is a front perspective view of a com-

bined radio cabinet and cigarette container showing my new design in closed position.

Figure 2 is a rear elevational view, and

Figure 3 is a view similar to Figure 1 showing the combined radio cabinet and cigarette container in open position.

I claim:

The ornamental design for a combined radio cabinet and cigarette container, substantially as shown.

HEIDI MARIENTHAL.
